UNITED STATES PATENT OFFICE.

FREDERICK C. NICKOL, OF DAYTON, OHIO, ASSIGNOR OF ONE-HALF TO BERNARD H. ZIEHLER, OF DAYTON, OHIO.

SHINGLE-BRACKET.

1,152,118.

Specification of Letters Patent. Patented Aug. 31, 1915.

Application filed March 7, 1914. Serial No. 823,055.

To all whom it may concern:

Be it known that I, FREDERICK C. NICKOL, a citizen of the United States, residing at Dayton, in the county of Montgomery and State of Ohio, have invented certain new and useful Improvements in Shingle-Brackets, of which the following is a specification, reference being had therein to the accompanying drawing.

This invention relates to shingle brackets of that type commonly employed to support a scaffold upon a roof while the same is being shingled. As is well known it is necessary that a shingle scaffold should be moved up the roof step by step as where row after row of shingles are applied to the roof. It is desirable that some support should be provided for the scaffold which will enable it to be quickly and easily attached to and detached from the roof and which will not injure the shingles. Numerous devices for this purpose have been proposed and many of these were designed to grip one of the shingles which had already been applied to the roof and form a support against which the scaffold could rest. The form of scaffold most commonly employed is a beam or scantling which is supported edgewise on the roof and forms a brace or support against which the workman may brace himself, his body resting upon the roof. In use two or more of the brackets are attached to the roof and spaced apart suitable distances and the scantling placed against the upper side of the brackets. Many of these devices propose to utilize the weight on the bracket to cause a gripping action on the shingle, but nevertheless they commonly fail because of the insufficiency of this gripping action which results in the bracket slipping under heavy pressure.

The object of the present invention is to provide a device of this character in which a very powerful gripping action will be had and the gripping member will be held in such a manner that it cannot spring or yield when in use and will not become distorted in such a manner as to lessen its efficiency after long use.

A further object is to so construct the device that the gripping member may be locked in its operative position in such a manner that there will be no danger of its releasing itself should the pressure thereon be relieved but which will cause an in-

creased gripping action as the pressure on the bracket increases.

In the accompanying drawings, Figure 1 is a longitudinal, sectional view, taken just inside one of the side members of a bracket embodying my invention; and Fig. 2 is a front end elevation of the device.

In these drawings I have illustrated one embodiment of my invention and have shown the same as comprising a base plate 1 adapted to have its forward portion inserted beneath a shingle on the sloping roof of a building. Rigidly secured to the base plate on opposite sides thereof and projecting upwardly and forwardly are two arms 2 which, in the present instance, are formed integral with the base plate. The forward portions of these arms are spaced away from the base plate 1, by cutting away the lower portions of the arms, so that the end of the shingle beneath which the base plate 1 has been projected may extend beneath the forward ends of the arms. Pivottally mounted between the arms or side members, 2, of the bracket is a clamping plate 3 spaced above the base plate 1 a distance sufficient to permit the entrance of the butt end of the shingle beneath which the base plate has been projected. In the present instance the clamping plate is mounted on a shaft 4 mounted at its ends in the arms 2. The clamping member 3 is provided with a gripping portion and, in the present form of the device, this gripping portion consists of a downturned front end portion 5 which is serrated or provided with teeth to enter the shingle and give an efficient gripping action. A pressure member or locking member is mounted on the arms 2 directly above the gripping portion of the clamping plate 3.

This locking member is here shown as a lever having its lower portion cam-shaped, as shown at 6, and pivotally mounted between the arms on a shaft 7. In the present instance the lever has two of these cam-shaped portions, one arranged near each of the side portions or arms 2. The lower cam-shaped portions of the lever are of such a character that when the upper portion or pressure arm 8 of the lever is moved forward a portion of the cam having a short radius will be brought above the clamping plate and it will be free to move upward out of engagement with the shingle. A second portion of the cam surface lying imme-

diately beyond the first-mentioned portion has a radius of such a length that when it is moved into contact with the clamping plate the teeth 5 will be forced into the shingle and a strong gripping action exerted on the shingle and the shingle will be clamped between the plate 3 and the base plate 1, the teeth preventing any slipping of the bracket relatively to the shingle. The bearing surface of the cam is so arranged with relation to the cam plate that it will engage the same directly above the gripping portion thereof so that the pressure will be exerted directly upon the gripping portion, or teeth, and these teeth will be locked firmly in engagement with the shingle. Heretofore it has been common to project the gripping surface of the clamping member some distance beyond the pressure or locking member. As a result the end portion of the clamping member could spring upward and free itself or partially free itself when unusual pressure was exerted thereon by the scaffold. Further, the repeated action of the pressure device upon the plate between its ends tends to curve this portion of the plate downwardly and lessen the efficiency of the gripping action of the teeth. By causing the pressure member or cam to bear upon the plate directly above the gripping portion thereof we not only prevent the distorting of the plate but exert a maximum of pressure on the gripping surface and prevent it from springing under any circumstances whatever. That portion of the cam which rests upon the clamping plate when the pressure device is in its normal locking position is substantially flat, as shown at 9, so that when the device has been moved into its locking position it will be held in that position and cannot be released therefrom without the application of considerable pressure to the upwardly extending portion 8 of the lever. Consequently, the lever will not spring forward or otherwise loosen itself when the pressure thereon is temporarily relieved. That part of the cam in the rear of the flattened portion 9 thereon is of a gradually increasing radius so that if unusual pressure is exerted upon the upper portion of the lever the latter will be moved about its axis and a gradually increasing pressure exerted upon the gripping portion of the clamping plate, this pressure increasing in proportion to the weight resting upon the scaffold. In the present form of the device I have provided a spring 10 to automatically retain the clamping plate in its elevated position to permit the placing of the bracket in position but obviously any suitable means may be provided for elevating the plate or may be merely engaged by the fingers and lifted. I have also provided the device at its rear end with spurs 11 which, in the present instance, are formed on

the rear ends of the arms 2 and bite into the shingles to further resist any tendency of the device to slide down the roof and to distribute the strains between two or more shingles.

The operation of the device will be readily understood from the foregoing description and it will be apparent that I have provided a very simple, yet highly efficient clamping shingle bracket. A maximum of gripping action is had for the pressure applied to the lever 8 and this pressure is held against accidental release. In actual practice it has been demonstrated that the shingle will break before the bracket will yield or slip from the shingle.

While I have shown and described one embodiment of the invention it will be understood that this has been chosen for the purposes of illustration only and that I do not desire to be limited to the details of construction shown and described, for obvious modifications will occur to a person skilled in the art.

Having thus fully described my invention, what I claim as new and desire to secure by Letters Patent, is:—

1. A device of the character described comprising a base plate having its forward end adapted to extend beneath a shingle, arms arranged on opposite sides of said base plate, having the lower edges of their rear portions secured to said base plate and having their forward portions spaced away therefrom, a clamping plate arranged between said arms, pivotally connected thereto at its rear end and having its forward portion free to move toward and away from said base plate, a lever pivotally mounted between its ends on the forward portions of said arms, having a cam-shaped lower part arranged to engage said forward portion of said clamping plate and also having an arm extending upwardly and forwardly from the axis of said lever and arranged to be engaged by a scaffold.

2. A device of the character described comprising a base plate having its forward end adapted to extend beneath a shingle, arms arranged on opposite sides of said base plate, having the lower edges of their rear portions secured to said base plate and having their forward portions spaced away therefrom, a clamping plate arranged between said arms, pivotally connected thereto at its rear end and having its forward portion free to move toward and away from said base plate, said forward portion being provided with depending prongs, a spring tending normally to elevate the forward portion of said plate, a lever pivotally mounted between its ends on the forward portions of said arms and having cam-shaped lower parts arranged adjacent to the respective arms to engage the forward

portion of said clamping plate directly above said prongs and also having an arm extending upwardly and forwardly from the axis thereof and arranged to be engaged by a scaffold.

3. A device of the character described comprising a base plate having its forward end adapted to extend beneath a shingle, arms arranged on opposite sides of said base plate, having the lower edges of their rear portions secured to said base plate and having their forward portions spaced away therefrom, a clamping plate arranged between said arms, pivotally connected there-
15 to at its rear end and having its forward portion free to move toward and away from said base plate, said forward portion being provided with depending prongs, a spring tending normally to elevate the forward portion of said plate, a lever pivotally mounted between its ends on the forward portions of said arms and having cam-

shaped lower parts arranged adjacent to the respective arms to engage the forward portion of said clamping plate directly 25 above said prongs and also having an arm extending upwardly and forwardly from the axis thereof and arranged to be engaged by a scaffold, said cam-shaped portions of said lever having intermediate flat 30 portions to rest upon said clamping plate when the latter is in its normal clamping position and having those portions lying beyond said flat portions of gradually increasing radii, whereby abnormal pressure 35 upon said scaffold will cause an increase of pressure upon said clamping plate.

In testimony whereof, I affix my signature in presence of two witnesses.

FREDERICK C. NICKOL.
